DESIGN FOR A COCKTAIL SHAKER CLOSURE

Edwin W. Fuerst, Toledo, Ohio, assignor to Owens-Illinois Glass Company, Toledo, Ohio, a corporation of Ohio

Application July 26, 1935, Serial No. 57,813

Term of patent 14 years

To all whom it may concern:

Be it known that I, Edwin W. Fuerst, a citizen of the United States and residing at Toledo, in the county of Lucas and State of Ohio, have invented a new, original, and ornamental Design for a Cocktail Shaker Closure, of which the following is a specification, reference being had to the accompanying drawing, forming a part thereof.

In the drawing:

Fig. 1 is a side elevational view of a cocktail shaker closure showing my design.

Fig. 2 is a top plan view thereof.

I claim:

The ornamental design for a cocktail shaker closure substantially as shown.

Signed at Toledo, in the county of Lucas and State of Ohio, this 24th day of July, 1935.

EDWIN W. FUERST.
